OVERTHROW CHECK FOR CALCULATING MACHINES

Original Filed Nov. 23, 1920 2 Sheets-Sheet 2

UNITED STATES PATENT OFFICE.

EDWIN F. BRITTON, JR., OF MAPLEWOOD, NEW JERSEY, ASSIGNOR TO MONROE CALCULATING MACHINE COMPANY, OF NEW YORK, N. Y., A CORPORATION OF NEW YORK.

OVERTHROW CHECK FOR CALCULATING MACHINES.

Original application filed November 23, 1920, Serial No. 426,043. Divided and this application filed September 2, 1921. Serial No. 497,864.

To all whom it may concern:

Be it known that I, EDWIN F. BRITTON, Jr., a citizen of the United States of America, resident of Maplewood, in the county 5 of Essex and State of New Jersey, have made a certain new and useful Invention in Overthrow Check for Calculating Machines; and I declare the following to be a full, clear, and exact description of 10 the same, such as will enable others skilled in the art to which it appertains to make and use the invention, reference being had to the accompanying drawings, and to 15 letters or figures of reference marked thereon, which form a part of this specification.

Figure 1 is a plan view of a calculating machine embodying the invention.

Figure 2 is a section on the line 2—2, 20 Figure 1.

Figure 3 is an enlarged detail side view of the positive over throw check, with adjacent parts of the machine.

The invention has relation to means for 25 preventing overthrow of the numeral wheels of a calculating machine, under momentum, during the registering operation, having for an object the provision of improved means for checking the wheels when subjected to impulses of varying extent and 30 speed.

Another object is the provision of a positive check which will require a minimum of idle adjustment in the operation of the 35 machine. Other objects and advantages will hereinafter appear.

The invention consists in the novel construction and combination of parts, as hereinafter set forth.

In the accompanying drawings illustrating 40 an embodiment of the invention applied to a machine constructed in accordance with the disclosure of co-pending application 426,043, of which the present is a divisional application, the numeral 3 represents an operating crank handle, adapted 45 to communicate motion to a train of equivalent gears 76, 75 and 74. Upon the shaft and fast with gear 75 is a smaller gear 80, meshing with a similar gear 81 mounted 50 rigidly upon the shaft 4 of the selecting or

primary gears 5. These gears 5 are arranged in sets of two, each set selectively positioned by a series of digital keys and connecting rack bars, as explained in the 55 reissue patent to Baldwin No. 13,841, the teeth of each set being arranged in approximately a half-circle, so that the gears 5 may mesh with intermediate gears 12 during approximately a half-rotation of 60 shaft 4, the other half rotation of said shaft being idle. The gears 12 mesh with and operate the gears of the numeral wheels 13.

Gear 74 is fast upon shaft 73, to which annuli *m* are also rigidly attached, these annuli serving to support laterally movable carrying teeth *j*, arranged in two oppositely pitched spirals each extending approximately one-fourth around shaft 73, a tooth 70 of each spiral series being adapted to engage its respective intermediate gear 12. Approximately the first quarter rotation of shaft 73 serves to move one series of carrying teeth *j* idly past the gears 12 and corresponds to a portion of the idle movement 75 of shaft 4. The next half-rotation of shaft 73 is also idle, and corresponds to the active or setting-up movement of shaft 4. The final quarter rotation of shaft 73 brings 80 the teeth *j* of the second series successively into position to act upon the intermediate gears 12, in case of lateral positioning of the teeth *j* by their carrying cams 21; this movement of shaft 73 corresponding to the 85 remaining idle movement of shaft 4, completing the cycle.

Reverse or subtractive rotation of the operating handle 3 will result in the same sequence of movements described for forward or additive rotation, except that the said first or idle series of carrying teeth *j* will now operate, and the second or other series will not act.

In order to provide for a sufficient number of banks of keys in a machine of the construction above described, and to obtain a satisfactory operation of the parts, it is necessary to operate the carry teeth *j* at considerably greater speed than the teeth 100 of the selector gears 5, the teeth *j* having a much longer leverage, so as to retain the

necessary intervals therebetween without allotting too great a portion of the cycle of operation to the carry.

To prevent overthrow of the numeral wheels under impulse of one or more of the teeth of primary selector gears 5, a spring brake 6 is employed, acting upon the teeth of the intermediate gears 12 in the manner described in the Patent No. 1,349,628, dated August 17, 1920. With the reduced speed of rotation of the primary gears made possible by the present invention it has been found that the braking tension of this spring may be reduced materially, provided carry overthrow checks are employed, made necessary by the carry teeth *j* moving more rapidly than the gears 5. Otherwise, where no carry overthrow checks used, the braking tension of the spring 6 would have to be increased instead of reduced, in order to check said numeral wheels against overthrow in carrying.

The carry overthrow checks in the present case consist of a series of arms 7, pivoted upon rod 15 and lying in the planes of the annuli *m* at the left-hand side of each tooth *j*. A cam extension 8 of each annulus *m* acts to throw the related arm 7 toward the intermediate gear immediately upon the completion of the carry action of the corresponding carry tooth *j*, a pin 9 at the end of said arm engaging between the teeth of the gear 12 at this time and being held by said cam to positively prevent overthrow.

The arms 7 constituting the carry overthrow checks are so mounted upon their shafts that when the cams 8 move from beneath said arms the latter will be frictionally held in position upon their shaft, in engagement with the intermediate gears, until said gears are rotated in a subsequent operation by the selector gears 5 or carry teeth *j*, when they will be moved from engagement with said gears into the position shown in Figure 3 of the drawings, where they will be frictionally held in position upon their shaft until moved again into engagement with the gears by the cams 8. This is of marked advantage, since should these arms be held normally in contact with the gears 12, as by spring means, the latter would resist movement of such gears throughout their actuation by the selecting and carry elements; while should they be held normally in disengaged position, as by spring means, the latter would resist movement of all of the carry annuli *m* once during each rotation of the crank, and should they be allowed to drop down through force of gravity after action of the cams 8 thereon, they would noisily vibrate and rattle.

The overthrow checks are so mounted and

positioned that when they are thrown to active position by the cams 8, the thrust of the gears 12 will be resisted by the supporting shaft 15 or the carry shaft 73, according to the direction of rotation of said gears.

Owing to the fact that the braking tension of the spring 6 is materially reduced, the machine is rendered more sensitive, smooth and easy running, these advantages being accentuated by the preservation of a uniform tension throughout the cycle of operation.

I claim:

1. In a calculating machine, selecting mechanism including driving elements, carry mechanism including driving elements, numeral wheels operated by said selecting elements and more rapidly by said carry elements, spring overthrow preventing means for said numeral wheels, and positively acting overthrow preventing means for said numeral wheels operable only during the carry operation.

2. In a calculating machine, selecting mechanism including driving elements, carry mechanism including driving elements, numeral wheels operated by said selecting elements and more rapidly by said carry elements, spring overthrow preventing means for said numeral wheels, and independent overthrow preventing means for said numeral wheels operable only during the carry operation.

3. In a calculating machine, numeral wheels, selecting mechanism including driving elements, carry mechanism including a shaft and driving elements and cams mounted thereon, gears operating the numeral wheels and operated in either direction of rotation by the selecting elements and carry elements, a shaft, overthrow checks mounted thereon and operated by said cams to engage said numeral wheel gears, said carry shaft or said check shaft taking the thrust of said gears, according to the direction of rotation.

4. In a calculating machine, a numeral wheel, operating means for said wheel including a gear, an overthrow check adapted to engage said gear, and means for effecting such engagement, said overthrow check being adapted to be held in engaged position until moved therefrom by said gear and in disengaged position until moved therefrom by said engaging means.

5. In a calculating machine, a numeral wheel, operating means for said wheel including a gear, a pivoted overthrow check adapted to engage said gear, and means for effecting such engagement, said overthrow check being held frictionally in engaged position until moved therefrom by said gear and in disengaged position until moved therefrom by said engaging means.

6. In a calculating machine, numeral wheels, selecting mechanism including driving elements, carry mechanism including driving elements, gears operating the numeral wheels and operated by the selecting elements and carry elements, and carry-overthrow checks adapted to engage said gears, and means for effecting such engagement, each overthrow check being held independently and frictionally in engaged position until moved therefrom by its respective gear and in disengaged position until moved therefrom by its respective cam.
- 5 25
- 10 8. In a calculating machine, selecting mechanism including driving elements, carry mechanism including driving elements, numeral wheels operated by said selecting elements and more rapidly by said carry elements, constantly active light tension spring checking means for the numeral wheels, and normally inactive positive carry-checking means for the numeral wheels including members held frictionally in active or inactive position.
